ALTERNATING CURRENT ELECTROMAGNET

Clarence T. Evans, Wauwatosa, Wis., assignor to
Cutler-Hammer, Inc., Milwaukee, Wis., a cor-
poration of Delaware

Application August 31, 1935, Serial No. 38,697

5 Claims. (Cl. 175—338)

This invention relates to alternating current electromagnets.

The invention has among its objects to improve such electromagnets in respect of the shading coils thereof and securement of such coils.

Another object of the invention is to improve such electromagnets in respect of the armatures thereof to avoid injury of the shading coils which commonly occurs through formation on the armatures of ridges which enter the slots in which the shading coils are mounted.

Other objects and advantages of the invention will hereinafter appear.

The accompanying drawing illustrates an embodiment of the invention which will now be described, it being understood that the embodiment illustrated is susceptible of various modifications without departing from the scope of the appended claims.

20 In the drawing:

Figure 1 is a side view of an electromagnet the coil whereof is shown in dotted lines;

Fig. 2 is a front view of that portion of the magnet frame of Fig. 1 carrying the shading coil;

Fig. 3 is an enlarged side view of the magnetic pole carrying the shading coil, and

Fig. 4 shows the face of the armature member of Fig. 1.

30 Referring to Fig. 1, the electromagnet shown therein is in general of well known form and hence details thereof have been omitted. It comprises a supporting frame 1 carrying laminae 2 of magnetic material to form a part of the magnetic circuit of the coil shown in dotted lines. Also it comprises an armature member 4 pivoted to the supporting frame at 5, said armature member carrying laminae 3 of magnetic material to form a part of the magnetic circuit of the aforementioned coil.

As shown in Fig. 2 the upper pole of the supporting frame presents a pole face comprising the laminae 2 confined in two groups between a center member 6 and side members 7 and 8, 45 these members comprising parts of the supporting frame. This pole face is rectangular and at a suitable distance therefrom there is formed in the pole an open slot 9 illustrated in Figs. 1 and 3 and more clearly in the latter view. This slot 50 which extends across the under side of the pole parallel to said pole face is provided to receive a portion of shading coil 10 and the pole has cut therein a second slot 11 extending through and transversely of its pole face to receive another 55 portion of said shading coil.

The shading coil 10 preferably is formed of laminae of brass soldered together with a soft solder enabling the laminae to be separated as hereinafter set forth, such a material being now on the market under the trade name "Laminum". 5 As illustrated in Fig. 2 the soldered together laminae are stamped to form a closed loop which as shown is of oblong form, although it is to be understood that the form may be varied as desired. Thus each lamina comprises a complete 10 and unitary closed loop which will be self-sustaining if its soldered connection with adjacent laminae melts or breaks.

Considering now assembly of the shading coil with the magnetic pole, the former after being 15 in part inserted into slot 9 is shifted to effect its insertion in part into the slot 11. Thereby provision is made for support of the coil which as shown is of such dimensions that it extends beyond the sides of the pole. The slot 9 may be 20 formed either for a loose or close fit of the coil. A suitable guard 13 may advantageously be inserted into the slots 9 and 11 ahead of the coil and a similar guard 14 may be inserted after the coil has been placed. The coil may be secured 25 as desired, but preferably it is secured by a metal retainer 15 inserted into slot 11 and swedged for retention therein. The retainer preferably extends entirely across the pole face and preferably is swedged substantially throughout its 30 length.

Securement of the coil by a swedged-in retainer as aforescribed has been found highly 35 advantageous in that the coil may be tightly seated in the slot without strains thereon likely to break the soldered connections of the laminae or to injure the laminae. Unless the coil is securely mounted at least in respect of a portion thereof it is likely to vibrate to such a degree as to cause breakage thereof. Of course with 40 the coil mounted as illustrated the parts thereof external of the pole as well as the part in slot 9 are subjected to considerable vibration and it has been found in practice that such vibration produces a shear between the laminae of such 45 external parts and that such shearing action aided by the heat of the electromagnet soon breaks the solder bond to free the unconfined portions of the laminae one from another. This, however, is an advantage rather than a disadvantage, 50 for the strains due to vibration are thus reduced to those capable of being set up in the very thin individual lamina and a very thin lamina may very readily be designed to withstand any such strains.

Referring to Fig. 4 showing the face of the armature to engage the slotted pole face hereinbefore discussed, said armature face comprises the laminae 3 confined in two groups between a center member 16 and side members 17 and 18, said members comprising parts of the armature 4. This armature face has a transversely extending slot 19 located therein to register with the slot 11 in the face of the pole carrying the shading coil. Accordingly it will be impossible for the metal of the armature laminae to build up a ridge capable of entering the slot 11 and pounding the shading coil as frequently happens where the armature laminations are of usual form.

15 What I claim as new and desire to secure by Letters Patent is:

1. In an alternating current magnet, a magnet frame having a pole with a slotted face, a shading coil for said pole formed of soldered together laminae, each lamina being unitary and in the form of a closed loop, said coil being passed through said slotted face for assembly with said pole and a retainer for said coil received by said pole through its said slotted face and swedged for 25 securing.

2. In an alternating current magnet, a magnet frame having a pole with a slotted face, a shading coil for said pole formed of soldered together laminae, each lamina being unitary and in the form of a closed loop, said coil having a portion inserted into said pole through said slotted face thereof and having portions outside of said pole and a retainer for said coil received by said pole through its said slotted face and swedged for 30 securing.

3. In an alternating current magnet, a magnet frame having a pole with a slotted face, a shad-

ing coil for said pole formed of soldered together laminae, each lamina comprising a single sheet metal stamping having the form of a thin flat closed loop, said coil having a portion thereof inserted into said pole through the slotted face thereof and having portions external of said pole and means to secure said coil in place leaving the external portions of said coil free for loosening of their laminae one from another under the influence of the heat and vibration of operation 10 of the magnet.

4. In an alternating current magnet, a magnet frame having a pole provided with two transversely extending slots, one an end face slot and the other a side face slot underlying the end face 15 of said pole, a shading coil for said pole formed of soldered together laminae, each lamina comprising a single sheet metal stamping having the form of a thin flat closed loop, said coil having a portion thereof inserted into said side face slot, 20 a portion inserted into said end face slot, and intermediate portions external of said pole, and means to secure said coil in said end face slot.

5. In an alternating current magnet, a magnet frame having a pole with a slotted end face, a 25 shading coil for said pole having a portion thereof inserted into said end face slot of said pole, a retainer for said coil extending substantially the full length of said slot and swedged in said slot and an armature member for said frame having 30 a face to engage said end face of said pole, said faces engaging in a single plane and having an area of engagement divided by said pole slot and said face of said armature member being recessed opposite the slot area of said pole face for 35 protection of the elements within said slot.

CLARENCE T. EVANS.
